Primary Examiner — Michelle E. Wilson*Assistant Examiner* — Sanjeev Paul(74) *Attorney, Agent, or Firm* — Joshua A. Stockwell, Esq.(57) **CLAIM**

The ornamental design for a pillow, as shown and described.

DESCRIPTION

FIG. 1 is a top, front perspective view of the pillow in accordance with the present invention;

FIG. 2 is a front view thereof;

FIG. 3 is a top view thereof;

FIG. 4 is a right side view thereof, it being understood that the left side view is the mirror image thereof;

FIG. 5 is a rear view thereof;

FIG. 6 is a left side elevation view thereof in use;

FIG. 7 is a top, front, right perspective view of the pillow in FIG. 1 shown in an alternate configuration;

FIG. 8 is a front view thereof;

FIG. 9 is a top view thereof;

FIG. 10 is a right side view thereof, it being understood that the left side view is the mirror image thereof;

FIG. 11 is a rear view thereof; and,

FIG. 12 is a left side elevation view thereof in use.

The elements depicted in broken lines in the various figures are included for environmental purposes only, and form no part of the claimed design.
